MILITARY INSIGNE OR SIMILAR ARTICLE

Elizabeth Will, Washington, D. C., assignor to the
United States of America as represented by the
Secretary of the Army

Application June 14, 1948, Serial No. 146,947

Term of patent 14 years

(Cl. D29—2)

To all whom it may concern:

Be it known that I, Elizabeth Will, a citizen of the United States and resident of the city of Washington, in the District of Columbia, have invented a new, original, and ornamental Design for a Military Insigne or Similar Article, of which the following is a specification, reference being had to the accompanying drawings, forming a part thereof.

Figure 1 is a front view of a military insigne, showing my new design;

Figure 2 is a top view of the same; and

Figure 3 is a side view of the same.

It is understood that my design may be embodied in such articles as an emblem, a badge, medal, medallion, plaque, or sign, without departing from the spirit of my invention.

The essential features of my design are shown in full lines.

I claim:

The ornamental design for a military insigne or similar article, as shown and described.

ELIZABETH WILL.
